William Lawrence, of Meriden, Connecticut.

Letters Patent.

The schedule referred to in these Letters Patent, and making part of the same containing a description in the words of the said William Lawrence of his improvement in giving light to Bimacles called "Lawrence's Bimacle Lamp."

To all to whom these presents shall come,

Be it known that I, William Lawrence, of Meriden in the County of New Haven and State of Connecticut a native citizen of said State and of the United States, have invented a new & useful improvement in giving light to Bimacles which I call "Lawrence's Bimacle Lamp" & that the following is a full and exact description of the construction & operation of said machine as invented or improved by me.

I. The lamp is composed of two shells, the outside shell containing a bowl, about six inches in diameter & two & a half inches deep with a hole in the bottom about two inches in diameter. The bottom of the bowl turned up is the top of the lamp. The inside shell is of a bell, or trumpet mouth shape, also of about six inches in diameter at the widest opening & of about two inches at the other, so that the openings of the two shells at top and bottom shall exactly correspond & these corresponding edges are to be closely & firmly soldered together forming by the swelling of the outer shell, a cavity for oil. —

Near the open orifice, on the top of the lamp is an opening about half an inch in diameter to four in oil & may be closed by a cork or screw stopper also on each side of the open orifice on the top are left, or formed, two or more springs about an inch in length and about one eighth of an inch broad, to receive corresponding tubes for wicks, these tubes are about three inches long descending about two inches into the oil chamber and rising over the open orifice in the top about one inch at an angle of about forty five degrees, thereby bringing the blaze of the wicks when inserted in the tubes, directly over the open orifice of the lamp, this whilst the light is diffused downward upon the compass is increased by reflection from the concave & brilliant sides of the inner shell,

the tubes may be made of common tin, shaped to fit the orifice and

for them, having two or more slots in the projecting part of each for the convenience of moving the wish & may be taken out for its invention and replaced at pleasure.

The body of the lamp or the shells may be made of any suitable metal from plates or castings. I prefer to cast the shells separate of hardware in moulds & when put together they are turned & well burnished or polished especially on the inner shells.

To produce the balance of the lamp when filled with oil, a rim of lead is cast in a hole mould, of a shape exactly fitted to the lower section of the inner space, between the shells weighing about seventeen ounces, which is inserted between the shells before they are soldered together.

This will over balance a pound of oil, which it is calculated the cavity may hold, and the horizontal level of the lamp when hung in the manner hereinafter specified will thereby always be preserved.

If this lamp is suspended for use, in the same manner & on the same principle as the marines compass is usually suspended viz, on two opposite arms projecting & extending, from near the top of the lamp, one on each side & terminating in pivot, inserted into the opposite side of a circle or hoop, about seven inches in diameter in which it freely vibrates, which hoop or ring, is also suspended on two pivots at right angles with the line of the first described pivot, & these last described pivots are attached to the side cap of the binnacle, or any other proper support.

By means of these pivots, the lamp thus suspended & balanced directly over the compass, will yield to the motion of the ship & always keep a horizontal position, & diffuse its light downward on the compass below it. — I claim as my invention & improvement the particular construction of the lamp as above specified and the application to it, of the common & well known principle of suspending the marines compass, as specified above, whereby the horizontal position of the lamp & the diffusion of the light downward on the compass, will be preserved & notwithstanding the rolling of the vessel, which invention, improvement & application are most useful & therefore to secure the benefit thereof, I desire to be Patent according to law. In testimony whereof I have made my name and the day when the application was made 1793 — John C. Smith
